UNITED STATES PATENT OFFICE.

WILHELM GROSS, OF FALL RIVER, MASSACHUSETTS.

WARP STOP-MOTION FOR LOOMS.

No. 898,358.

Specification of Letters Patent.

Patented Sept. 8, 1908.

Application filed August 16, 1907. Serial No. 388,810.

To all whom it may concern:

Be it known that I, WILHELM GROSS, a subject of Germany, residing at the city of Fall River, in the county of Bristol and State of Massachusetts, have invented certain new and useful Improvements in Warp Stop-Motions for Looms, of which the following is a specification, reference being had therein to the accompanying drawing.

10 This invention relates to warp stop-motion for looms, and has for its object to provide means for stopping the loom when a warp thread breaks or becomes unduly slack.

A further object of the invention is to arrange the mechanism so that a movement of the stop actuating device will also cause the warp threads to be opened longitudinally to clearly indicate the position of the broken warp end.

20 The essential feature of my invention is that a drop wire or the like is suspended from each warp thread over two adjacent parallel notched bars, one of which bars is arranged to reciprocate at regular intervals 25 transversely across the loom, the other of said bars being normally at rest is so connected with the shipper lever that when a thread breaks and one of said suspended wires drops, it first engages a notch of the reciprocating bar and is carried to one side until 30 said notch registers with a corresponding notch in said second bar, when the wire drops into both notches and locks the two bars together, whereby a further movement of the 35 first bar will also move the second to stop the loom.

It will be seen by this motion that a double object is attained. First, the drop wire, which was allowed to fall by the broken 40 thread, is drawn to one side to clearly indicate the position of the broken ends, and second, this mechanism which causes said warps to open is also arranged to stop the loom.

A further object of my invention is to apply this motion, which includes the two movable notched bars, to the heddle frame whereby the heddles may be operated upon, if desired, to be moved to either one side or the other of its normal position by the breaking 50 of a warp thread, to clearly indicate the position of the broken warp end, and at the same time trip the shipper lever to stop the loom.

Another feature of my invention is that 55 the reciprocating bar is operated by means whereby it may be drawn to one side and

held for a predetermined period and then allowed to move in the opposite direction and rest for another period. This timing device nicely controls the movement of the reciprocating bar whereby the breaking of a thread is caused to stop the loom at the proper time.

The invention is fully set forth in this specification and more particularly pointed out in the appended claims.

In the accompanying drawings: Figure 1—is a view in outline illustrating a portion of the loom, and showing my stop motion and indicating device as applied to the heddles, 70 and heddle frame. Fig. 2—is a side elevation of the heddle frame showing my device attached thereto, also the latch which is designed to operate the stop motion. Fig. 3—is a perspective view showing one of the heddles in position to lock the two sliding bars together. Fig. 4—is a side elevation of the two sliding bars and their supporting trough as applied to drop wires, also showing means connected to one of said bars for operating 80 the shipper lever to stop the loom, and also means for reciprocating the other bar whereby the same is drawn to one side and held for a predetermined period and then allowed to return in the opposite direction and rest for 85 another period. Fig. 5—is a sectional end view of said bars and a drop wire in position thereon. Fig. 6—is an end view sectional on line 6—6 of Fig. 1, showing the ratchet and cam by which the operating bar receives 90 its reciprocating motion. Fig. 7—is a modification showing another means for operating the ratchet 29. Fig. 8—is a side elevation of the same.

Referring to the drawings at 1 is the lay, 2 the breast beam and 3 the shipper lever. The warp 4 is run in the usual way from the beam 5 over the rods 6 through the heddles 7 and 8. The drop wires 9 are shown in Figs. 4 and 5 as being thin flat blades having an elongated eye 10 through which the actuating bars are adapted to pass. This blade is also provided with a small hole 10^a through which the thread 4 is passed that suspends or supports said blade while said thread is taut and in its normal position.

Slidably mounted in a U-shaped trough 11 is a thin flat bar 12 provided with teeth 13 on its upper edge. At 14 is a similar bar provided with corresponding teeth 15 which are arranged to register with those in bar 12. These bars are designed to set transversely

across the loom, the bar 12 being caused to reciprocate at regular intervals by any suitable or convenient means, and bar 14 being normally at rest. When this device is applied 5 to drop wires, as illustrated in Fig. 4, I preferably use a mechanism such as herein shown for reciprocating this bar 12, which is that of a pair of intermediate gears 16 and 17. At 10 each revolution of the gear 16 the gear 17 receives a half revolution and then rests for a predetermined period. A crank 18 is supported on the same shaft 19 with the gear 17, to which one end of a cord 20 is attached, the opposite end being connected 15 to the bar 12 whereby said bar is drawn to one side at regular intervals and returned by means of the spring 21, the time of the return action being also controlled by said intermediate gears. The second bar 14 is normally 20 at rest and is connected to the tripping finger 22 by the cord 23, whereby when a drop wire 9 is allowed to fall by the breaking of a thread, said wire engages the teeth of both bars locking them together causing the 25 tripping finger to be actuated to operate the shipper lever 3 to stop the loom. Another feature of my invention is that these movable actuating bars 12 and 14 may be arranged to operate the heddles equally well as 30 to operate the drop wires. When applied to the heddles the U-shaped trough 11 is supported at either end in the heddle frame 8 as shown in Fig. 2. These heddle frames may be operated in the usual way by means of the 35 cam 24 and levers 25 which are connected to the lower end of said frames through the cord 26, causing said frames to work up and down to open the shed.

The reciprocating bar 12 is arranged to be 40 moved first in one direction and then in the other at each downward movement of the heddle frame, said bar being operated through the auxiliary lever 27, to which it is connected, by the cord 28.

45 Mounted on the frame actuating lever 25 is a ratchet wheel 29, see Figs. 1 and 6, to which ratchet is connected the cam 30, both being mounted and fixed to the short shaft 31 whereby they will operate in unison. A 50 pawl 32 supported from the floor or other convenient place, stands upright and is arranged to engage a tooth of the ratchet wheel each time the lever 25 descends and rotates said ratchet and cam one-quarter 55 turn to operate the auxiliary lever. This cam is arranged with two opposite flat sides and two opposite projecting sides, whereby at the first downward stroke of the heddle frame the auxiliary lever 27 is pressed 60 downward some distance further than the frame lever, to draw over the reciprocating bar 12, and by said cam is caused to remain in that position during the return stroke, and on the second downward stroke the cam 65 is again turned allowing the reciprocating

bar to return by the action of the spring 21 and remain in that position during the return stroke, and so on at each stroke of the frame the reciprocating bar is caused to move back and forth through the eye of each 70 heddle. It will be seen by this arrangement that the two levers 25 and 27, which are both pivoted on the shaft 33, are caused to move in unison one with the other and on the first downward stroke of the same the 75 auxiliary lever is caused by said cam to be moved further than the frame lever 25, and on the next downward stroke is allowed to return to its first position.

It will be observed that the heddles are 80 held up clear of this reciprocating bar only while the frame is below the center of its travel, therefore this reciprocating bar is only allowed to move on the last half of the downward stroke, as shown by the position 85 of the pawl. The stop motion, as applied to this heddle frame, consists of a latch lever 34 which is pivoted in said frame at 35, and is also connected at its upper end 36 to the bar 14. The lower end of said lever is provided with a hook or projecting lip 37 which is adapted to engage the arm 38 of the knee lever 39 and through the connecting rod 40 operate the tripping finger 22 to stop the loom upon the next upward stroke of the 95 heddle frame.

The operation of the invention may be more fully described as follows: This device pertains directly to the operating of a loom when a warp thread breaks, both to 100 stop the loom and also at the same time to indicate the position where the broken warp thread is located.

The device may be operated either by the use of drop wires, which may be located at 105 any convenient place along the warp threads, or the same may be arranged to operate the ordinary heddles in the heddle frame. In either case two serrated bars retained in a suitable casing pass through an eye in each drop 110 wire. One of these bars is caused by suitable means to reciprocate and move back and forth across the warp at regular intervals. The second bar, which is adjacent to the first bar, is normally held at rest and is provided 115 with teeth which are adapted to register with those of said reciprocating bar. This second bar may be connected in any convenient way so that a movement of the same will operate the shipper handle to stop the loom. The 120 drop wires are all suspended by the warp threads and normally held clear of the teeth of the reciprocating bar. When one of these threads become broken or unduly slack and allows its wire to drop into engagement with the teeth of the reciprocating bar, this wire is naturally moved to one side by 125 said bar until it falls also into engagement with the tooth of the second bar thereby locking the two together. A further move- 130

ment of this reciprocating bar will draw the warp threads and the adjacent drop wires to one side making a wide opening in both to clearly indicate the position of said broken 5 warp ends, at the same time this side motion also causes the shipper handle to be actuated to stop the loom at the proper time. The same result is obtained when this mechanism is applied to the heddles. The reciprocating 10 bar is drawn to one side on the latter part of the downward stroke of the heddle frame and when a thread is broken the heddle falls upon the teeth of this reciprocating bar and as above described, locks the two bars together 15 drawing the second bar also to one side where both are retained by means of the cam 30, while the heddle frame again ascends. The moving of this second bar from its normal position to one side causes the lever 34 to be 20 moved to throw out its hooked end 37 and upon the next upward stroke of the heddle frame operate the levers 38 and 22 to stop the loom. Another method of operating the ratchet wheel 29 is that illustrated in Figs. 25 7 and 8, whereby a pin 41 is placed in the cam 24, which at the proper time engages the teeth of the ratchet wheel 29 rotating the cam 30 and causing the auxiliary lever 27 to be thrown downward at the proper time to 30 draw over the toothed bar in the heddle frame.

I do not confine myself to either of the above shown methods of operating the shipper handle to stop the loom as any convenient 35 or desirable means may be used for this purpose whereby a movement of this second bar may throw off the shipper handle to stop the loom.

This device is simple and practical of construction and effective in its operation.

Having thus described my invention, what I claim as new and desire to secure by Letters Patent, is:

1. In a warp stop motion for looms, a reciprocating bar, means for operating the same, a second bar arranged beside the former bar and normally at rest, a single support for both bars, and means whereby the breaking of a thread will automatically lock 45 both bars together, whereby the second bar is moved with the first bar to cause the loom to stop.

2. In a warp stop motion for looms, a bar, means for reciprocating said bar, a second 55 bar normally at rest, and means whereby the breaking of a thread will automatically lock both bars together to move said second bar and open the warp thread to indicate the position of the broken ends and also cause the 60 loom to stop.

3. In a warp stop motion for looms, a reciprocating bar, means for operating the same, a second bar normally at rest, and means for automatically locking both bars

together, whereby the second bar is moved 65 with the first bar to cause the loom to stop, said locking means being normally supported in inoperative position by the warp threads.

4. In a warp stop motion for looms, a reciprocating bar, means for reciprocating said bar laterally across the loom, a shipper handle, a second bar for operating said handle to stop the loom, said bar being normally at rest and means whereby the breaking of a thread will automatically lock both bars together 75 whereby they will both be moved to open the warp thread to indicate the position of the broken ends and also cause the loom to stop.

5. In a warp stop motion for looms, a bar, means for reciprocating said bar, a second bar normally at rest, heddles adapted to engage the warp threads, and means whereby when a thread breaks said heddles will cause said first bar to move the second bar and 85 open the warp thread to indicate the position of the broken ends and also cause the loom to stop.

6. In a warp stop motion for looms, a serrated bar, means for reciprocating said bar, a second serrated bar normally at rest, heddles adapted to engage the warp thread, and means whereby when a thread breaks or becomes slack a heddle will fall and lock said first and second bars together and move said 95 second bar to stop the loom, said heddle also being drawn to one side to open the warp and indicate the position of the broken ends.

7. A warp stop motion for looms, comprising the heddle frame, heddles in said frame, means whereby said heddles are suspended by the warp threads when the frame is down, a bar, means for reciprocating said bar when said heddles are suspended, a second bar normally at rest, and means whereby when a thread breaks or becomes slack a heddle will fall and lock said bars together, whereby they are moved in unison and stop the loom.

8. A warp stop motion for looms comprising the heddle frame, heddles in said frame, means whereby said heddles are suspended by the warp threads when the frame is down, a bar supported in said frame, means for reciprocating said bar only when said heddles 110 frames are down, a second bar normally at rest, and means whereby when a thread breaks or becomes slack a heddle will fall and cause said bars to move in unison and stop the loom, said heddle also being drawn 115 to one side to open the warp and indicate the position of the broken ends.

9. A warp stop motion for looms, comprising the heddle frame, heddles in said frame, means whereby said heddles are suspended by the warp threads when the frame is down, a bar supported in said frame, means for reciprocating said bar only when said heddles 125

- are suspended and retaining the same first on one end and then at the opposite end of its stroke for a predetermined period, a second bar normally at rest, and means whereby 5 when a thread breaks or becomes slack a heddle will fall and cause said bars to move in unison and stop the loom, said heddle also being drawn to one side to open the warp and indicate the position of the broken ends.
- 10 10. A warp stop motion for looms, comprising the heddle frame, heddles in said frame, means whereby said heddles are suspended by the warp threads when the frame is down, a serrated bar, means for reciprocating said bar, a second serrated bar normally at rest, and means whereby when a thread breaks or becomes slack a heddle will fall and lock said first and second bars together and move said second bar to stop the 15 loom, said heddle simultaneously being drawn to one side to open the warp and indicate the position of the broken ends.
11. A warp stop motion for looms, comprising the heddle frame, heddles in said frame, means whereby said heddles are suspended by the warp threads when the frame is down, a bar supported in said frame, means for reciprocating said bar only when said heddle frames are down, a second bar normally at rest, and means whereby when a thread breaks or becomes slack a heddle will fall and cause said bars to move in unison, and means in said frame whereby the movement of said second bar will cause a further movement of 20 said frame to stop the loom.
12. A warp stop motion for looms, comprising the heddle frame, heddles in said frame, means whereby said heddles are suspended by the warp threads when the frame is down, a bar, a cam for controlling the movement of said bar when said heddles are suspended, a second bar normally at rest, and means whereby when a thread breaks or be- 25 30 35
- comes slack a heddle will fall and cause said bars to move in unison and stop the loom. 45
13. A warp stop motion for looms, comprising the heddle frame, heddles in said frame, means whereby said heddles are suspended by the warp threads when the frame is down, a cam for reciprocating said frame, 50 a bar supported in said frame, a ratchet wheel operated in time with said cam for reciprocating said bar only when said heddle frames are down, a second bar normally at rest, and means whereby when a thread breaks or becomes slack a heddle will fall and cause said bars to move in unison, and means in said frame whereby the movement of said second bar will cause a further movement of 55 said frame to stop the loom. 60
14. A warp stop motion for looms, comprising the heddle frame, a cam operated lever attached to said frame, heddles in said frame, means whereby said heddles are suspended by the warp threads when the frame is down, a bar supported in said frame, a cam actuated lever for reciprocating said bar only when said heddle frames are down, a ratchet for moving said latter cam, and means including said ratchet and cam whereby said 65 latter lever is caused to travel in time with said first lever and receive a greater stroke, a second bar normally at rest, and means whereby when a thread breaks or becomes slack a heddle will fall and cause said bars to 70 move in unison, and means in said frame whereby the movement of said second bar will cause a further movement of said frame to stop the loom. 75

In testimony whereof I affix my signature 80
in presence of two witnesses.
